CLAIM

The ornamental design for a hand-held ventilator, as shown and described.

DESCRIPTION

FIG. 1 is a top view of a hand-held ventilator, showing our new design;

FIG. 2 is a bottom view thereof;

FIG. 3 is a right isometric view thereof; and,

FIG. 4 is a left side view thereof.

The broken lines in the figures are for purposes of illustrating portions of the hand-held ventilator and form no part of the claimed design.

1 Claim, 4 Drawing Sheets
